UNITED STATES PATENT OFFICE.

WILLIAM J. ELSOM, OF CORTLAND, NEW YORK, ASSIGNOR TO GEORGE H. GARRISON AND CHARLES M. DE VANY, OF CORTLAND, NEW YORK.

FERTILIZER-DISTRIBUTER.

No. 830,773.

Specification of Letters Patent.

Patented Sept. 11, 1906.

Application filed February 12, 1906. Serial No. 300,566.

To all whom it may concern:

Be it known that I, WILLIAM J. ELSOM, of Cortland, in the county of Cortland, in the State of New York, have invented new and useful Improvements in Fertilizer-Distributors, of which the following, taken in connection with the accompanying drawings, is a full, clear, and exact description.

This invention relates to the class of fertilizer-distributors in which the apron or floor of the vehicle-body is terminated at the ends of the body and receives a reciprocating motion which carries it forward in the vehicle-body to form the bottom thereof for receiving the load of fertilizer and subsequently moves said apron gradually rearward to discharge the fertilizer through the rear end of the body.

The object of the invention is to provide simple and efficient means for automatically arresting the motion of the longitudinally-reciprocating apron at its arrival at its normal or loading position in the body of the vehicle and at the end of its delivery of the fertilizer from said body; and to that end the invention consists in the novel construction and combination of the component parts of the invention hereinafter described, and illustrated in the accompanying drawings, in which—

Figures 1 and 2 are elevations of opposite sides of a machine equipped with my invention. Figs. 3 and 4 are longitudinal sections showing the apron in position for controlling its propelling mechanisms to automatically reverse the movement of the apron. Fig. 5 is an enlarged side view of the propelling mechanism of the apron, some of the parts being broken away to expose more important features of the mechanism. Fig. 6 is an enlarged detached plan view of the reversing mechanism. Fig. 7 is a side view of the bracket on which the clutch-shifting levers are fulcrumed. Fig. 8 is a fragmentary face view of the disk gear which transmits motion from the traction-wheels. Fig. 9 is a detached side view of the yoke which connects the clutch-shifting lever to its actuating-lever. Fig. 10 is an enlarged vertical section through the center of the left traction-wheel and the gear which transmits motion to the beater. Fig. 11 is a plan view of the longitudinally-movable plate and clutch-shifting lever actuated by said plate. Fig. 12 is an

inner face view of the collar which is fastened 55 to the axle B' and transmits motion from the traction-wheel to said axle. Fig. 13 is a transverse section of said collar, and Figs. 14 and 15 are face views of the clutch mechanism which transmits motion from the traction-wheel at the right side of the machine to the rear axle.

A represents the box or body for carrying the fertilizer to be distributed.

B B denote the traction-wheels, which are 65 mounted loosely on the rear axle B'.

a represents the longitudinally-movable apron, which is provided with the following board D on its front end to convey the fertilizer to the rear of the body A.

C is the usual beater, which serves to scatter the fertilizer delivered from the rear end of the body, and E denotes the usual adjustable tail-board.

The apron a extends from end to end of the 75 body and forms the bottom or floor thereof when in its normal position, as shown in Fig. 3 of the drawings. Said apron consists of transverse slats attached to endless chains a' a', which are carried on sprocket-wheels b 80 and b', attached to transverse shafts c and c', mounted in suitable bearings on the ends of the body A. The wheels b are rigidly attached to the shaft c, which will be hereinafter referred to as the "apron-shaft." This 85 shaft receives rotary motion, which is reversible to propel the apron rearward and cause it to discharge the fertilizer through the rear end of the body A and then forward to its normal position in the body A.

The apron, as well as the beater, is actuated by the rear axle B', which is journaled in suitable bearings on the body A and receives rotary motion from the two traction-wheels B B by means of suitable clutch mechanisms which maintain the apron and beater in motion to continue distributing the fertilizer from the machine while being turned from a straightforward course.

The clutch mechanism at the left of the 100 machine is preferably of the form shown in Figs. 10, 11, 12, and 13 of the accompanying drawings, in which 1 represents a gear-wheel, which is mounted loosely on the rear axle B' and engages a pinion 2, which is formed on 105 the hub of a sprocket-wheel 3, pivoted to a stub-shaft 4, rigidly sustained on the body A. A chain 5 transmits motion to a sprocket-

wheel 6, which is fastened to the shaft of the beater C, as shown in Fig. 2 of the drawings. Between the hub of the gear-wheel 1 and hub of the traction-wheel B is a collar 7, mounted 5 on the axle B' and pinned or otherwise rigidly attached thereto. The outer side of said collar has projecting from it a spider 8, to which are pivoted pawls 9 9 9, engaging an annular ratchet 10, secured or formed in a 10 cavity in the aforesaid hub, and thus causing the axle B' to rotate with the traction-wheel. The inner side of the collar 7 is formed with a clutch-face 11, which faces a correspondingly-shaped clutch-face on the adjacent side 15 of the hub of the gear-wheel 1, which is movable to and from the collar to engage and release the same. The shifting of the gear-wheel 1 is effected by means of a lever 12, fulcrumed on the side of the body and having 20 one end engaged with a circumferential groove 13 in the hub of the gear-wheel. The opposite end of said lever is in engagement with an oblique slot 14 in a longitudinally-movable plate 15, connected to the body A 25 and controlled by means of a hand-lever U, pivoted to the side of the body near the driver's seat and connected by a rod U' to the upper end of lever V, pivoted to the body, the lower end of which lever is connected by 30 a rod V' to the plate 15.

The clutch mechanisms at the right side of the machine consist of pawls 16, pivoted to the disk O, which is rigidly attached to the axle B', said pawls engaging a ratchet 17 in 35 the hub of the adjacent traction-wheel B. (Shown in Figs. 14 and 15 of the drawings.) The disk O has projecting from its inner face a plurality of concentric annular rows of teeth t t, as shown in Fig. 8 of the drawings. 40 Near the toothed side of said disk is a radially-disposed shaft d, which is journaled at one end in a stationary block d', which loosely embraces the axle B'. The opposite end of said shaft is journaled in a bearing on a 45 bracket I, firmly attached to the side of the body A and formed with the aforesaid block d'. The shaft d is provided with a spline e and has mounted on it a pinion J, which is adapted to slide lengthwise of said shaft and 50 is provided with a groove engaging the spline e to compel the shaft to turn with the pinion. By sliding the pinion toward or from the axle B' to engage different rows of teeth t the speed of revolution of the pinion J is varied 55 as may be desired, and by sliding the said pinion to a position which prevents engagement with the teeth of the disk the rotation of the pinion is arrested. Said adjustment is effected by means of hand-lever R on the 60 forward end of the body and convenient to the person in charge of the machine. A rod R' connects the hand-lever R with a bell-crank S, pivoted to the bracket I and connected with a ring S', seated loosely in a circumferential groove in the hub of the pinion 65

J. To the outer end of the shaft d is rigidly attached a worm J', which engages a worm-gear L, pivoted on a stub-shaft L', projecting from the bracket I. To the side of the worm-gear L is attached a sprocket-wheel N, which 70 is connected by a chain N' with a sprocket-wheel P, which is mounted loosely on the apron-shaft c and is formed with clutch member c' on its inner face, as is shown in Fig. 6 of the drawings. 75

On the apron-shaft c is a longitudinally-movable duplex clutch-collar f, which is provided with a groove engaging a spline f' on the shaft c. By sliding said clutch-collar into engagement with the clutch member c' 80 of the wheel P the apron-shaft c receives rotary motion which propels the apron a rearward. At a proper distance from the inner side of the sprocket-wheel P is a bevel-gear g, which is also loosely mounted on the shaft c 85 and has on its outer face a clutch member g'. h represents a shaft which is disposed radially in line with the axial centers of the axle B' and apron-shaft c and journaled near its ends in bearings h' h', fastened to the side 90 of the body A, as shown in Fig. 6 of the drawings. On the front end of the shaft h is adjustably mounted a pinion i, which can be placed to engage different rows of teeth t of the disk O. To the rear end of the said shaft 95 is attached a bevel-pinion i', which meshes with the bevel-gear g, and thus causes said gear to be rotated in a direction reverse from the rotation of the sprocket-wheel P, which reverse motion is transmitted to the apron-shaft c when the clutch-collar f is shifted into 100 engagement with the clutch member g' of the gear g. The engagement of the pinion i with the gear-wheel g moves the apron forward to its normal position in the body A. The gear-wheel g is sufficiently distant from the sprocket-wheel P to allow the clutch-collar f to be placed in a neutral position to prevent 105 its engagement with either of the clutch members g' and c', as shown in Fig. 6, and thus 110 maintain the apron-shaft dormant. The clutch-collar f is automatically placed in said position by instrumentality of mechanisms actuated by the traveling apron. This is effected by means of a trip-lever k, which is 115 pivoted at the center of its length on a transverse shaft or suitable support c' on the front of the machine. To the ends of this lever are connected rearwardly-extending rods k' k'', which are coupled to each other at their 120 rear end by means of a chain l, passing around the rear portion of the periphery of a suitable supporting-wheel l', mounted loosely on the apron-shaft c. To the under side of the front 125 end of the apron a is rigidly attached a block a', through which the rod k' freely passes. To the ends of said rod are firmly secured two collars a' a''. The collar a'' is placed in position to be pushed forward by the block a' when the apron a arrives at its normal posi- 130

tion, as shown in Fig. 3 of the drawings. The other collar a^3 is disposed to be pushed rearward by said block when the front end of the apron arrives at the rear end of the body 5 A, as illustrated in Fig. 4 of the drawings. The rod k' , moving with the said collars, rocks the lever k , which causes the rod k^2 to move reverse from the rod k' . Along opposite sides of the shaft h extend longitudinal levers $o\ o$, which are pivoted at their front ends to a bracket p , fastened to the outer side of the body A. The rear ends of said levers have pins or lugs $r\ r$ projecting laterally from the inner sides of the levers and engaging 15 a circumferential groove u in the clutch-collar f .

n represents a bell-crank which is pivoted to a suitable bracket attached to the body A. This bell-crank has a short arm which is connected by a yoke or bifurcated link n^2 to the levers $o\ o$ near the rear ends thereof, as shown more clearly in Fig. 6 of the drawings. A longer arm of the bell-crank extends transversely under the body A and is connected to 25 the rod k^2 . The hereinbefore described movement of said rod causes the bell-crank n to move the rear ends of the levers $o\ o$ laterally sufficient to shift the clutch-collar f to a position which prevents it from engaging 30 either of the two clutch members g' and c^2 , as shown in Fig. 6. In this position the clutch-collar is left when the front collar a^2 has been pushed forward by the block a' on the apron. The body A is thus in condition to be loaded 35 to convey the fertilizer to the field.

T denotes a foot-lever which is pivoted to the footboard T' and has its lower end connected by a rod T² to the upper end of the trip-lever k .

40 When it is desired to distribute the fertilizer from the machine while traversing the field designed to receive the fertilizer, the operator pushes the lever T into a position which tilts the trip-lever k so as to cause the lower rod k^2 to push the clutch f into engagement with the clutch member c^2 of the sprocket-wheel P by means of the bell-crank n and levers $o\ o$. The apron-shaft c is thus rotated to impart rearward movement to the 45 apron. Upon the arrival of the front end of the apron at the rear end of the body the block a' encounters the collar a^3 , and in pushing the same rearward the rod k' tilts the trip-lever k so as to draw the lower rod k^2 forward, and thereby actuate the bell-crank n sufficiently to shift the clutch f from the 55 clutch member of the sprocket-wheel P and place said clutch into a neutral position, and thus arrest the movement of the apron after 60 the fertilizer is distributed therefrom. The operator subsequently sets the apron in motion to return it to its normal position in the body by moving the foot-lever T into a position which causes the trip-lever k to draw the 65 rod k^2 forward, and thereby throw the clutch

f into engagement with the clutch member g' of the gear g , which imparts forward motion to the apron.

What I claim as my invention is—

1. The combination with the apron and traction-wheels, of two transmitting-wheels mounted loosely on one end of the apron-shaft, a clutch-collar splined to the apron-shaft and adapted to engage said transmitting-wheels one at a time, two separate mechanisms actuated by one of the traction-wheels and imparting reverse motions to the two transmitting-wheels, and means disposed to be actuated by the apron at its arrival at the front and rear end portions of the machine and shifting the clutch-collar as set forth. 75

2. The combination with the apron and loosely-mounted traction-wheels, of two transmitting-wheels mounted loosely on the end of the apron-shaft at one side of the machine and provided with clutch members on their adjacent sides, a duplex clutch-collar splined to the apron-shaft between the transmitting-wheels to engage said wheels one at a time, two sets of mechanisms disposed at the aforesaid side of the machine and transmitting motion from the traction-wheel to the aforesaid wheels on the apron-shaft, a trip-lever disposed to be actuated by the traveling apron, longitudinal rods actuated by the trip-lever, and levers actuated by said rods and shifting the clutch-collar on the apron-shaft as set forth. 95

3. The combination with the apron, and traction-wheels, transmitting-wheels mounted loosely on one end of the apron-shaft, a clutch-collar splined to the apron-shaft to engage the transmitting-wheels one at a time, two sets of mechanisms actuated by the same traction-wheel and imparting reverse motions, to the transmitting-wheels, a centrally-pivoted trip-lever disposed to be actuated by the traveling apron, longitudinal rods connected to the ends of the trip-lever, means actuated by said rods to move the clutch-collar to its neutral position and a manually-operated lever connected to the trip-lever to shift the clutch-collar into operative position as set forth. 110 115

4. The combination, with the apron-shaft and traction-wheels, of a gear-wheel and a sprocket-wheel both mounted loosely on the apron-shaft and provided with reversely-formed clutch members on their adjacent sides, a spline on the said shaft between the loosely-mounted wheels, a duplex clutch-collar sliding on the splined portion of the shaft, a gear mounted on the axle of the traction-wheel and receiving motion from the said traction-wheel, a sprocket-wheel actuated by said gear and connected by chain with the aforesaid loosely-mounted sprocket-wheel, a shaft disposed radially with the axial centers of the traction-wheel and apron-shaft, gears 120 125 130

on opposite ends of said shaft and engaging respectively the gear on the axle and the gear on the apron-shaft, means for shifting the aforesaid clutch-collar into and out of engagement with the clutch members on the loosely-mounted gear-wheel and sprocket-wheel, a trip-lever pivoted at the center of its length, a rod connected to one end of said trip-lever and extending lengthwise of the apron, 5 collars attached to opposite ends of said rod, a block attached to the apron to contact alternately with said collars, a longitudinally-disposed rod connected to the opposite end of the trip-lever, and means actuated by 10 said rod and shifting the aforesaid clutch-collar.

5. The combination with the apron, its propelling-shaft and traction-wheels, of a gear-wheel and a sprocket-wheel both mounted loosely on the apron-shaft and provided 15 on their adjacent sides with reversely-shaped clutch members, a spline on said shaft between the loosely-mounted wheels, a duplex clutch-collar sliding on the splined portion of the shaft, a gear actuated by one of the traction-wheels, a shaft extending from said gear to the gear-wheel on the apron-shaft, pinions 20 on the ends of said shaft and engaging said gear and gear-wheel, a sprocket-wheel receiving motion from the aforesaid traction-wheel, 25 a chain transmitting motion from said sprocket-wheel to the sprocket-wheel on the apron-shaft, a lever disposed to shift the clutch-collar, a block attached to the front 30 end of the apron, a trip-lever pivoted at the center of its length, a rod connected to one end of said trip-lever and extending lengthwise of the apron, collars attached to the ends 35 of said rod and disposed to contact with said block, a longitudinally-disposed rod connect-

ed to the opposite end of the trip-lever and actuating the clutch-shifting lever as set forth.

6. The combination, with the apron-shaft, rear axle and traction-wheels, of a gear-wheel and a sprocket-wheel both mounted loosely on the apron-shaft and provided with reversely-formed clutch members on their adjacent sides, a spline on the shaft between the loosely-mounted wheels, a duplex clutch-collar sliding on the splined portion of the shaft, a gear mounted on the axle of the traction-wheels and receiving motion from said traction-wheels, a sprocket-wheel actuated by said gear and connected by chain with 50 the loosely-mounted sprocket-wheel, a shaft disposed in line with the axial centers of the traction-wheels and apron-shaft, gears on opposite ends of said shaft engaging respectively the gear on the axle and the gear 55 on the apron-shaft, longitudinal levers pivoted at their front ends to the body and engaging at their rear ends the clutch-collar, a bell-crank having arms of different lengths and its short arm connected to the rear ends 60 of the longitudinal levers, a trip-lever pivoted at the center of its length, a block attached to the front end of the apron, a longitudinal rod connected to the upper end of the trip-lever, collars attached to the ends of said rod 65 and disposed to contact with said block, a rod connected to the lower end of the trip-lever and to the aforesaid bell-crank, a chain coupling the rear ends of said rods, and a 70 loosely-mounted wheel supporting said chain, 75 as set forth and shown.
